US00D890775S

(12) **United States Design Patent** (10) **Patent No.:** **US D890,775 S**
Clay (45) **Date of Patent:** **** Jul. 21, 2020**

(54) **COMPUTER DISPLAY WITH GRAPHICAL USER INTERFACE**

(71) Applicant: **Bruce Clay**, Simi Valley, CA (US)

(72) Inventor: **Bruce Clay**, Simi Valley, CA (US)

(**) Term: **15 Years**

(21) Appl. No.: **29/662,778**

(22) Filed: **Sep. 7, 2018**

(51) **LOC (12) Cl.** **14-04**

(52) **U.S. Cl.** USPC **D14/485**

(58) **Field of Classification Search**

USPC D14/485-495; D20/10, 11, 22-33, 39, D20/40

(57) **CLAIM**

The ornamental design for a computer display with graphical user interface, as shown and described.

DESCRIPTION

The FIGURE is a front view of my new design for a computer display with graphical user interface.

The dot-dash broken-line perimeter illustrates a computer display and forms no part of the claimed design. The remaining dashed broken lines illustrate portions of the graphical user interface and form no part of the claimed design.
